United States Patent Office.

RICHARD A. YORK, OF READING, MICHIGAN.

Letters Patent No. 76,576, dated April 7, 1868.

IMPROVED CRIMPING-MACHINE.

The Schedule referred to in these Letters Patent and making part of the same.

TO ALL WHOM IT MAY CONCERN:

Be it known that I, RICHARD A. YORK, of Reading, Hillsdale county, State of Michigan, have invented a new and useful Machine for Crimping Boots, and known as an "Extension Crimping-Machine;" and I do hereby declare that the following is a full, clear, and exact description of the construction and operation of the same, reference being had to the annexed drawing, making a part of this specification, in which—

Figure 1 is a longitudinal extension.

Figure 2 are the rubbers with V-spring.

Figure 3 is form, with extension-blocks, draw-blocks, fastening-plates, gripes, thumb-screw, screw-lever, springs for holding extension-plates to form, and stock.

A A, rubbers; B B, knuckle-joint; C C, rounded knuckle; D, V-spring; E, enlarged and concave end of rubbers; F, form; G G, extension-block; H H H H, fastening-plates; I I I, movable gripes; J J J, thumb-screw; K K, grooves; L, draw-block; N N, flanges on draw-block; O, screw passing through draw-block; P, lever to turn screw; R R, straps; S S, springs to hold extension-blocks to place; T, stock; U, opening to allow jaw to pass through; V, jaw passing over draw-block L; Y Y Y Y, opening in stock, to allow straps R R to pass through; X X, hinges, fastening extension-blocks to form; 1, lower roller; 2, upper roller; 3, foot-lever; 4, cross-bar; 5, rubber or hand-lever.

To enable others skilled in the art to make and use my invention, I will proceed to describe its construction and operation.

I construct my "extension crimping-machine" by a framework of wood, in such a manner as to have two rollers, as 1-2, a lower and an upper. One, the lower roller, 1, contains a lever, 3, with cross-bar 4. The upper roller, 2, also contains a lever, 5, with mortise, 6, which contains two metallic rubbers or crimpers, a a, consisting of shafts and enlarged end, which is placed in lever, large end downward, and they are attached to each other by knuckle-joint B where they pass through lever 5; and also at top of shaft is a rounded knuckle, C, which receives the end of a V-spring, D, and which spring is used to extend upper end of shafts. The lower ends are enlarged, as represented at E, by two lateral shafts passing out in a circular manner, making an angle, passing back to main shaft, and uniting at lower end in such a manner as to form a rounded end, and the enlarged surfaces are concaved out on their inner side in such a manner as to fit form in crimping.

Form F consists of the common form, cut down on the back and foot of form, and two extension-blocks, G G, fastened to form at top and toe at X, forming a fulcrum at each end respectively, and each block reaching to or near the angle in form, and on each side extension-blocks, G G, are iron fastening-plates, H H H H, which are used to fasten leather on extension-blocks by means of movable gripes, I I I, which are secured to blocks by straps of iron, which are tightened by thumb-screw J J J. At the inner ends of extension-blocks G G are two grooves, K K. Between the extension-blocks G G is a draw-block, L, with two flanges, N N, which work in grooves K K, and, by means of screw O, worked with lever P, extends draw-block, and flanges extend extension-blocks G G, V-jaw passing over draw-block O, to fasten leather at corners R R, two straps passing over form F, through stock and around cross-bar 4, used to hold leather on form, and to hold form in stock T.

U, opening for jaw V; Y Y Y Y, opening for straps R R; springs S S, to hold extension-blocks in place, all constructed as above described, and as shown in the accompanying drawing, and work by standing left side to machine.

Leather being wet, straps R R being thrown over top of front post, place leather on form F, place straps over form, put left foot on lever 3, bring down leather to form, take hold of shaft below knuckle C with left hand, hold lever 5 near end with right hand. Now, bring down lever, guiding rubbers with left, to divide at the angle of form, passing down each side, work up and down until you can secure leather at point on draw-block L, pass jaw V over leather, tighten by turning screw O, gripes I I I being turned down, so as to allow fastening-plates H H H H to lie down flatwise, place edges of leather along extension-plates G G, turn up plates, also gripes I I I, and tighten with thumb-screw J J J. Now turn screw O, alternately working lever 5 with rubbers until work is completed.

What I claim as my invention, is—

1. The combination of the form F, spring-hinged extension-blocks G G, having grooves K, hinged extension-plates H, adjustable gripes I, adjustable draw-block L, having flanges N N and jaw V, substantially as and for the purpose specified.
2. The rubbers A, constructed as described, in combination with the spring D, substantially as and for the purpose specified.
3. The rubbers A, in combination with the slotted arm 5, roller 2, and form T, as herein described, for the purpose specified.
4. The combination of the rubbers A, form F, slotted and grooved V-shaped stock F, straps R, rollers, and treadle, substantially as described, for the purpose specified.
5. The device for crimping leather, constructed and combined to operate substantially in the manner and for the purpose described.

RICHARD A. YORK.
